UNITED STATES PATENT OFFICE.

DAVID W. HUDSON, OF GREEN BAY, WISCONSIN.

PAPER-ROLLING MACHINE.

Application filed March 7, 1922. Serial No. 541,846.

To all whom it may concern:

Be it known that I, DAVID W. HUDSON, a citizen of the United States, residing at Green Bay, county of Brown, and State of Wisconsin, have invented new and useful Improvements in Paper-Rolling Machines, of which the following is a specification.

This invention relates to improvements in paper rolling machines of the type adapted to be used in winding toilet paper, paper towels, wrapping paper, etc., upon suitable cores.

It is the object of this invention to provide a machine whereby the operator will be enabled to wind paper rolls more speedily than has heretofore been possible. As will hereinafter be explained, a machine embodying this invention winds paper at high speed in a substantially continuous operation, the transfer from one roll to the next being accomplished without an appreciable loss of time.

It is more particularly the object of this invention to provide in a paper winding machine a multiple spindle device having means for turning the head and tail stocks simultaneously to bring any spindle into operative position, and an improved centering and clutching device adapted to facilitate the substitution in driving position of each spindle successively.

Further objects of this invention are to provide a simple and efficacious machine semi-automatic in its action whereby the clutch, after having been disengaged from one spindle, cannot be moved to operative position again until the succeeding spindle is centered therewith; and to provide such a machine designed, particularly as to the controlling devices, for the maximum possible convenience of the operator.

In the drawings:

Figure 1 is a side elevation of a machine embodying this invention and adapted for use in forming rolls of toilet paper.

Figure 2 is a plan view of the same.

Figure 3 is a detail view of that portion of the machine with which this invention is immediately concerned, as viewed along the line of sight indicated by the arrow in Figure 1.

Figure 4 is an elevation of the head stock.

Figure 5 is a plan of the same.

Figure 6 is an elevation of the tail stock.

Figure 7 is a plan of the same.

Like parts are identified by the same reference characters thruout the several views.

The machine frame 1 carries at its rear a set of brackets 2 which are provided at 3 with open journals for the reception of the 60 trunnions 4 of the supply or parent roll 5. The lead of paper from the roll 5 is passed over the matrix roller 6 and maintained taut thereon by the pressure of clamping rollers 7 and 8, while perforating blades 9 carried by the star wheel 10 are successively driven thru the paper into registry with suitable matrices in roller 6. The several elements above noted are driven in co-ordination by suitable gearing from a power shaft 12. A 70 roller 13, likewise power driven, rests against a block 14 constituting a retarding device which effectually prevents the appearance of any slack in the winding rolls. Roller 13 is mounted in a frame so connected 75 to handle 15 as to be raisable by the operation of said handle to relieve the pressure and tension on the paper upon occasion.

The roll winding device proper is disposed upon a sub-frame including a pair of forwardly projecting arms 16 attached to the main frame 1 as shown in Figure 1.

In the forwardly projecting arms 16 is journalled a shaft 17 to which are secured the head stock 18 and the tail stock 19. The 85 head stock 18 comprises a disk which bears upon its periphery suitable journals 20 for a number of live spindles 21. The tail stock, as is best illustrated in Figures 6 and 7, is preferably constructed in the form of a 90 spider, the arms of which carry suitable dead spindles 22. Each dead spindle is maintained in registry with one of the live spindles of the head stock by reason of the fact that the head and tail stocks are keyed 95 to the same shaft. The head and tail stocks, being mounted for rotation with shaft 17 and being fast thereto, are adapted to be turned as a unit to bring any of the live spindles 21 into an operative driven relation 100 to the driving means hereinafter to be described. A hand wheel 23, integral with the tail stock 19, is preferably provided to facilitate the manipulation of the head and tail stock, to bring the live spindles successively 105 into operative position.

An extension 24 of the arm 16, which supports head stock 18, has provision for a bearing 25 for the axially movable rod or pin 26, and also carries a bearing sleeve 27 110

within which the tubular power shaft 28 is disposed. A disk 29 fast to shaft 28 is preferably faced with leather, as indicated at 30, which contacts with one face of a 5 pulley 31 driven by a belt 32. See Figure 2. A knurled nut 34 is threaded upon the exterior of the bearing sleeve 27 and carries spring pressed pins 35 by which resilient pressure can be exerted thru a ball floated 10 disk 36 upon the face of pulley 31 opposite to that which bears against the leather faced disk 29. By this means an adjustable and resilient pressure can be exerted upon said pulley determinative of the torque which 15 will be imparted frictionally by said pulley to the tubular shaft 28 thru the leather faced disk 29.

At the inner end of the tubular shaft 28 is a clutch member 38 which may be 20 conveniently constructed in the form of a flat plate so mounted as to be slidable axially with respect to said tubular shaft while connected for rotation therewith. A shaft 39 extends thru the center of shaft 28 and is 25 provided at its inner end with a head portion 40 which is operatively connected to the plate 38 above referred to. A spring 41 confined between a shoulder of the tubular shaft 28 and the head 40 upon shaft 39 30 tends to force said head and the plate like clutch member carried thereby inwardly toward the operative position of engagement of said clutch.

Each of the spindles 21 is provided upon 35 its outer face with one or more notches 42 whereby the spindles are adapted to receive motion from clutch member 38 when said spindles are in alinement with shaft 28, and when the clutch member 38 is allowed to be forced by spring 41 into its 40 operative position as shown in Figure 3.

A clutch operating lever 45 is provided with a fulcrum at 46 and is pivoted at 47 to a rod 48 which is disposed axially within 45 the tubular shaft 17 upon which the head and tail stocks are mounted, as is clearly shown in Figure 3. The rod 48 is provided with an extended bearing within shaft 17 and passes entirely thru said shaft. At 50 its end, rod 48 carries a shifting arm 49 which is rigidly connected to said rod and to the rod 26, which is journalled at 25 in the supporting arm 16. The end of the shifting arm 49 is forked at 50 or is otherwise 55 loosely engaged within a collar 51 carried by the end of the axially movable clutch operating shaft 39. It will be clear that when the handle 45 is moved to the left (as viewed in Figure 3) the rod 26 and the 60 shaft 39 will also move to the left, retracting the clutch member 38. A spring 52 bearing against one of the supports 16 serves to return handle 45 to its normal position when the grasp of the operator is released.

65 Attention is directed to Figure 4. It will

be noted that the head stock 18 is provided with a number of openings 53 each of which is disposed in predetermined relationship to one of the live spindles 21. The arrangement is such that when a given live spindle 70 21 is in exact alinement with the driving shaft 28 the corresponding opening 53 will register with the end of the longitudinally slidable rod 26. The opening 53 and the end of said rod are preferably tapered to 75 facilitate the exact alinement of the drive shaft and live spindle following the entry of the end of the rod into the opening 53.

It is particularly to be noted that the arrangement is such that as long as rod 26 is 80 not inserted in one of the openings 53, the shifting arm 49 to which rod 26 is rigidly attached will maintain the clutch member 38 out of operative position where it can in no wise interfere with the rotative movement of the head and tail stocks for the purpose of positioning a new live spindle for rotation.

The dead spindles 22 are provided at 85 their inner ends with openings for the reception of the reduced end 55 of a mandrel 56. A ball bearing 57 may be provided within each dead spindle to permit the free rotation of the mandrel therein. To facilitate the insertion and withdrawal of the 90 mandrels, the dead spindles 22 are preferably so constructed as to be longitudinally movable within the tail stock. Springs 58 normally press each spindle inwardly and the heads of bolts 59 are adapted to contact with cover plates 60 to limit the extent of possible inward motion.

Each live spindle 21 is provided at its inner end with a square sided recess 61 adapted to engage the squared ends 62 of the 100 mandrels 56. It will be obvious that the operator will be able to manipulate each mandrel 56 into position very readily by first inserting its rounded end 55 into the bearing within the dead spindle 22 and forcing said dead spindle outwardly to a sufficient extent to permit the introduction of the squared end 62 of the mandrel into the opening in live spindle 21 designed to receive it. The spring 58, exerting a continuous inward pressure upon the dead spindle, will hold the mandrel in position until it is released by the operator.

Carried by the machine frame 1 below the arm 16 is a semi-cylindrical glue pot 65 within which is disposed a roller 66 mounted upon spring supported bearings 67. This roller lies in the path of card board tubes carried by mandrels 56 upon which the paper is to be wound. When the head and tail stocks are rotated each of the tubes will in turn be brought into contact with the roller, which will deposit glue upon the exterior surface of the tubes.

Upon the machine frame, best shown in 130

Figures 1 and 2, is a transverse shaft 70 rotatable by a handle 71. A wheel 72 fast to the shaft carries a metallic ribbon 73 to which is attached a spring 74 tending to hold lever 71 in the raised position shown. An arm 75 which is made fast to shaft 70 carries at its end a block 76 adapted to be moved by handle 71 to bring the strip of paper coming from the parent roll 5 into contact with the freshly glued surface of the properly positioned card board tube upon which the paper is to be wound.

The operation of this machine is as follows:

15 The paper strip unwound from the parent roll 5 is passed thru the various perforating and tensioning devices in the manner already described and is engaged with the freshly glued surface of a suitable card board tube carried by a mandrel 56 in the position designated by the letter A in Figures 1, 2 and 3. The lever 45 is now released to allow clutch member 38 to move into operative driving relation to the designated 25 live spindle 21 whereupon the strip of perforated paper passing thru the machine is wound upon its card board tube.

When the roll of paper has reached its proper size the operator grasps lever 45 and moves it to his left to disengage the clutch and release the rotatable head and tail stocks from the positioning pin or rod 26. The operator can now utilize the hand wheel 23 upon the tail stock to turn the 35 head and tail stocks simultaneously counter clock wise, as viewed in Figure 1. At the first movement of handle 23 he may release lever 45; and the positioning pin 26, sliding upon the outer surface of the disk-like 40 head stock 18, will retain clutch member 38 in inoperative position.

When hand wheel 23 has been sufficiently rotated to bring the newly wound roll of paper to the position indicated at B, a 45 freshly glued cardboard tube will have come to position A with its supported mandrel and live spindle in alinement with the drive shaft 28. At this point the positioning pin 26 will come into registry with the tapered 50 opening 53 and will enter said opening allowing the clutch member 38 to engage the jaw 42 of the given live spindle 21. Any shock resulting from the sudden engagement of the clutch will be absorbed by the slipping of pulley 31 relative to the leather faced disk 29, the amount of such slippage 55 being adjustable by means of nut 34.

In Figures 1 and 2, the operation above described has just taken place. It will be noted that a freshly glued cardboard tube appears at A and a full roll is shown at B. The strip of paper with which the full roll has been wound has not yet been broken. To start the new roll it is only necessary for 60 the operator to pull handle 71 into the posi-

tion in which it appears in these drawings. The block 76 is thereby lowered and brings the paper strip into contact with the glued surface of the rotating tube at A. The paper strip immediately becomes fast upon 70 the tube and begins to wind thereon, severing itself from the roll previously formed. The full roll may be held against a possible unwinding by the operator.

It will be noted that during the time required for the winding of a roll in position A the operator will have time to remove the full roll from position B and to insert in its place upon the mandrel in such position a fresh card board tube. With each movement of the head and tail stocks a full roll is brought to the position for removal by the operator, a fresh cardboard tube is carried to the device which covers its surface with glue, and a freshly glued tube is 85 brought to the operative driven position where paper is wound thereon.

It is desired to emphasize the fact that the controlling devices and particularly the arrangement whereby the clutch is held inoperative until the live spindle is alined with the power shaft greatly facilitate the operation of a machine of this kind. The operator, having thrown out the clutch and started to turn the head and tail stocks is 95 enabled to forget the clutch knowing that it will be automatically re-engaged at the proper time. There is, therefore, no need to move any lever twice in a given sequence of operations and the care of the machine is thereby so simplified as to enable the work to be done at comparatively high speed.

I claim:

1. In a paper rolling machine having a supporting standard and a rotatable carrier supported therefrom and provided with a head stock and a plurality of rotatable spindles thereon, latch mechanism including an axially movable rod for interlocking the head stock and supporting standard, a power shaft journaled in the standard and axially movable for selective connection with said spindles and disconnection therefrom, means connecting said rod with said power shaft for unitary axial movement while permitting rotation of said shaft, and means including a lever for moving said rod, whereby when the rod is moved to permit rotation of the carrier the power shaft will be disconnected from said spindles simultaneously with the movement of the rod.

2. In a paper rolling machine having a rotatable carrier provided with a disk-like head stock and a plurality of spindles rotatably mounted thereon, latch mechanism for locking said carrier against rotation and including an axially movable rod mounted in a stationary bearing, said rod having one end adapted to ride upon a face of the head

stock when such head stock is being rotated, power transmitting mechanism including a shaft having a stationary bearing and adapted for axial movement to and from 5 selective connection with said spindles, said rod and shaft being connected together for their simultaneous axial movement, whereby the carrier can be released to permit rotation thereof and the rod and shaft held in carrier 10 releasing position by the head stock thereof.

3. In a paper rolling machine having supporting standards and a rotatable carrier provided with a hollow shaft mounted in the standards and extending therethrough, said 15 carrier being provided with a head stock having a plurality of apertures equi-distant from each other and a corresponding number of spindles rotatably mounted in the head stock, the combination with an axially 20 movable power shaft carried by one of said standards and with which any of said spindles may be axially aligned and connected, of a pulley revolvably mounted on said power shaft, a clutch member secured to the power 25 shaft and adapted for engagement with the pulley, an axially movable rod extending through the hollow shaft, an axially movable pin having a bearing in one of the standards and one end adapted to be received 30 into either of the apertures in the carrier, an arm rigidly connected with the rod and pin and having forked connection with the power shaft, and means for moving said rod axially, whereby the power shaft may be 35 disconnected from the spindle and the pulley and the pin disengaged from the carrier to permit rotation thereof.

4. The combination with a supporting frame, of a hollow shaft journaled therein, 40 a carrier having a disk like head stock secured to said shaft and provided with a plurality of apertures equally spaced from each other and from the axis of the shaft, a rod journaled in said shaft and movable 45 axially therethrough, and a pin journaled in the supporting frame and having one end rigidly connected with the rod and its other end adapted to be received into any of the apertures in said head stock.

5. In a paper rolling machine, a supporting standard, a rotatable head stock having a plurality of spindles thereon, an axially movable power shaft, clutch mechanism for engaging the power shaft with either of said 55 spindles, an axially movable pin adapted to interlock the head stock and supporting standard, and means for moving said power shaft and pin simultaneously.

6. In a paper rolling machine the combination with a rotatable head stock and work carrying spindles therein, of a power driven element adapted for selective operative connection with said spindles, a lock including a bolt adapted to engage said 65 head stock and adapted to secure it in a

plurality of positions with said element aligned with respective spindles, and a clutch adapted when operative to engage said element with a spindle aligned therewith, said clutch being connected with said bolt for simultaneous movement between operative and inoperative positions. 70

7. The combination with a supporting frame, of a hollow shaft journaled therein, a disk-like head stock rotatable with 75 said shaft and provided with suitable recesses in its exterior face, a rod movable longitudinally thru said shaft, a locking pin connected to said rod and movable therewith, and a spring urging said rod and a pin toward head stock locking position, said pin being adapted to bear against the exterior face of the head stock and to be maintained thereby in retracted position except when engaged in one of said recesses. 80

8. The combination with a supporting frame, of a hollow shaft journaled therein, a disk-like head stock rotatable with said shaft, and recessed at predetermined points, a rod movable longitudinally thru said shaft, a lever adapted to effect the movement of the rod, a locking pin attached to the rod and movable therewith, to and from engagement with the walls of the recess in the head stock, rotatable spindles journaled in said head stock, a power shaft, clutch mechanism whereby said power shaft may be connected to any of said spindles which is aligned therewith, and means operable by the movement of said rod and pin for engaging and disengaging said clutch means in synchronism with the insertion and withdrawing of said pin from any of said recesses. 95

9. In a paper rolling machine provided with a plurality of spindles carried by a rotatable head and tail stock unit, and a power shaft with which each of said spindles may be aligned, the combination of a clutch associated with said power shaft 105 whereby said shaft may be connected to a spindle in alignment therewith, locking means adapted to secure said head and tail stock against rotation when any of said spindles are in alignment with said shaft, mechanism connecting said locking-means and said clutch whereby said clutch will be maintained in its disengaged position until said locking means is operative, and means normally urging said locking means toward 110 its operative position, whereby the locking of said head and tail stocks and the engagement of said clutch will be automatically effected. 115

10. In a paper rolling machine provided with a plurality of spindles carried by a rotatable head and tail stock unit, and a power shaft with which each of said spindles may be aligned, the combination of a clutch associated with said power shaft 125 120 130

whereby said shaft may be connected to a spindle in alinement therewith, locking means adapted to secure said head and tail stock against rotation when any of said 5 spindles are in alinement with said shaft, mechanism connecting said locking means and said clutch whereby, said clutch will be maintained in its disengaged position until said locking means is operative, means 10 normally urging said locking means toward its operative position and said clutch toward engagement and adapted to effect the automatic operation of these parts when a spindle is brought into alinement with the 15 power shaft, driving means loosely mounted upon said power shaft adapted for connection with a source of power, and means for establishing a frictional driving connection between said driving means and said power shaft, whereby the shock of the 20 automatic engagement of said clutch may be absorbed, if said shock is excessive.

11. In a device of the character described,

the combination with a revoluble head stock and rotatable work supporting spindles 25 carried thereby, of a bearing surface on said head stock provided with bolt receiving apertures, a bolt pressed toward said surface and receivable in said apertures to lock said head stock, a power driven element 30 positioned for alignment with a selected spindle when said bolt is operative to be engaged in an aperture of said head, a clutch adapted when operative to engage said element with a spindle in alignment therewith 35 and positive motion transmitting connections between said bolt and said clutch whereby they will move simultaneously between operative and inoperative positions, said bolt being adapted to ride inoperative 40 on said surface and to become automatically operative upon reaching an aperture whereby said clutch is automatically engaged to rotate an aligned spindle when said head stock becomes locked.

DAVID W. HUDSON.
